UNITED STATES PATENT OFFICE.

JOHN JOSEPH SCOLLAN, OF NEWARK, NEW JERSEY.

RELEASING DEVICE FOR LAUNCHING-CRADLES.

1,394,228.

Specification of Letters Patent.

Patented Oct. 18, 1921.

Application filed May 3, 1920. Serial No. 378,583.

To all whom it may concern:

Be it known that I, JOHN JOSEPH SCOLLAN, a citizen of the United States, residing at Newark, N. J., in the county of Essex,

5 State of New Jersey, have invented certain new and useful Improvements in Releasing Devices for Launching-Cradles; and I do hereby declare the following to be a full, clear, and exact description of the invention, 10 such as will enable others skilled in the art to which it appertains to make and use the same.

One object of this invention is to provide a launching cradle for ships which may be 15 readily released after it has cleared the launching ways. A further object is to provide a poppet construction for the launching cradle which, upon the release of the cradle, will float off to the sides of the 20 launched ship and become recoverable for use in connection with the launching of other ships.

To this end the after-poppets of the launching cradle are secured together while 25 the ship is on the ways but are released from one another during the launching operation when the poppets are about to clear the end of the ways. The poppets are preferably constructed in such a manner as to 30 prevent the loss, during launching, of any timber or other material of which they may be constructed.

The poppets, in accordance with this invention, may be secured together by means 35 of cable lashings and in this case the cables comprising the lashings are preferably attached to a poppet then looped about a pin and then secured again to the same poppet. In this manner, the pin serves to complete 40 the cradle between the poppets on either side of the aft of the ship when it is still on the ways. The cables attached to each poppet should be so disposed about the pin that substantially equal tension is main- 45 tained in all of the cables forming the lashings, thereby tending to retain the pin in a position in which it may readily be withdrawn from between the cables to release the cradle and permit the poppets to float 50 off to each side of the launched ship. It should be understood that one or more poppets may be used on either side of the aft of the ship and one or more pins may be used to release the cradle formed by the 55 cables and the respective poppets.

This invention is adaptable for use in connection with the launching of ships of any tonnage when such ships are launched in the usual manner from ground ways and it has the advantage that the ship may be 60 launched in more shallow water than would otherwise be possible without danger of the poppets sticking or fouling in the mud and doing damage to the hull of the ship or to the poppets themselves. The stern of a ship 65 is usually of such a contour as will enable it readily to cut through the mud at the bottom of such shallow water until the launching operation proceeds to the stage at which the inherent buoyancy of the ship will 70 float it.

The use of this invention is especially advantageous in connection with the launching of modern standardized fabricated steel ships in which case, the lines or contour of 75 each ship are substantially the same and require only slight alterations, if any, of recovered poppets used in previous launchings, in order that they may be used for the launching of other ships. This, of course, 80 results in a considerable saving in time and labor and enables the cost of production of such ships to be lessened proportionately.

The main features of this invention, as 85 well as the important and novel details thereof, will be understood from a consideration of the following description of the preferred embodiment of the invention, reference being had to the accompanying drawings:

Figure 1 illustrates a ship on the launching ways;

Fig. 2 illustrates a launched ship, together with the after poppets floating adjacent to its sides;

Fig. 3 is a vertical cross section view of the stern of a ship on the launching ways;

Fig. 4 is an enlarged sectional view of the launching cradle lashings.

Fig. 5 shows the lashing cables of the 100 launching cradle looped about a pin.

In Fig. 1 a ship 1 is shown on the launching ways 2 supported in an upright position at its stern by the poppets 3 and 4, together with the cable lashings 5 and 6 and 105 coacting poppets (not shown) located on the other side of the ship, thereby forming the launching cradle. As is well known, when the sliding way is released in the usual manner, and the wedges 7 are withdrawn, 110

the ship will slide down the launching way 2 into the water. During the launching operation, the pin 8, which completes the launching cradle formed by the poppet 3 and its coacting poppet on the opposite side of the ship together with the cables 5, is withdrawn by means of a cable 9 attached to the end of the pin and to a point on the ways. This withdrawal operation is shown 10 in the dotted position of the ship 1 just as the after-poppet 3 is clearing the launching ways. The poppet 3, which is constructed in such a manner that none of the timbers forming the poppet become separated from 15 the structure when released, floats off and may be towed to shore or salvaged in any suitable manner. The coacting poppet 3^a, shown in Fig. 3, corresponding to poppet 3 but located on the opposite side of the ship 20 floats off in a similar manner when the cradle is released and it also becomes recoverable. Likewise, poppet 4 and its coacting poppet also become recoverable in the manner described in the case of poppet 3. The 25 poppet 4 and its coacting poppet, together with the cable lashing 6 form a cradle which may be released by a pin and cable (not shown) identical with the pin 8 and cable 9, the lashing arrangement preferably being 30 such that the release is effected after the poppet 4 clears the end of the launching ways.

In Fig. 2 the after poppets 3 and 4 are shown floating adjacent to the sides of the 35 launched ship after the launching operation has been completed. Any convenient means may be used to tow these poppets to shore and so recover them for use in connection with the launching of other ships.

40 In Fig. 3 the stern of the ship 1 is shown supported by the poppet 3 and its coacting poppet 3^a forming a launching cradle with the cable lashings 5 and the pin 8. As has been pointed out, the wedges 7 are withdrawn when it is desired to launch the ship and the cable 9 serves to withdraw the pin 8, which releases the cradle and permits the poppets 3 and 3^a to float off to each side of the launched ship.

50 In Fig. 4, the cable lashing 5 is shown blocked away from the keel and sides of the ship 1 in order that no damage may be done to the plates of the vessel when the pin 8 is withdrawn from between the cable lashings 5.

Fig. 5 shows a method of looping the cable lashings 5 about the pin 8, the cables being disposed about the pin in such a manner as to enable it to be readily withdrawn by the cable 9 when the after-poppet of the launching cradle clears the end of the launching ways.

In the operation of the device, the ship 65 which is constructed of the usual type of keel blocks, has the sliding ways positioned and

thereafter the poppets are placed on such ways. Subsequently, the wedges 7, are driven between the poppets and sliding ways in order to lift the ship from the keel blocks, whereupon it begins to slide into the water. The rope 9 is of such length that the pin 70 8 of each device will not be withdrawn until the ship is afloat.

It is to be understood that various modifications may be made in the specific means shown for releasing the launching cradle without departing from the spirit and scope of this invention and further that the poppet construction and cradle may be altered in any manner to accommodate ships of various tonnages or ships having sterns of a contour different from the ship illustrated in connection with the preferred embodiment of 75 this invention.

I claim:

1. A launching cradle for ships comprising an after-poppet for each side of the ship, means for securing said poppets together while the ship is on the ways, and means co-operable with the ways for automatically releasing said poppets from each other during the launching operation whereby the poppets float off to the sides of the launched ship.

2. A launching cradle for ships comprising a poppet for each side of the aft of the ship, lashing for securing said poppets together while the ship is on the ways and means co-operable with the ways for automatically releasing said lashing during the 95 launching of the ship whereby the poppets become detached from each other and float off to each side of the launched ship.

3. A launching cradle for ships comprising a poppet for each side of the aft of the ship, lashing for securing said poppets together while the ship is on the ways, said lashing consisting of a plurality of cables attached to each poppet, a pin about which the cables are looped and means for withdrawing said pin from between the cables during the launching operation whereby said poppets become detached from one another and float off to each side of the 100 launched ship.

4. A launching cradle for ships comprising a poppet for each side of the aft of the ship, cables for securely lashing said poppets together while the ship is on the ways, said cables being attached to the respective poppets, a pin about which the cables are looped, and a cable having one end attached to the pin and the other end attached to the fixed way whereby said cable is adapted to withdraw the pin from between said cable loops during the launching operation when the poppets clear the end of the launching ways.

5. A launching cradle for ships comprising a plurality of poppets for each side of 130

the aft of the ship, cable lashings for securing said poppets together while the ship is on the ways, said lashings being attached to the respective poppets, a plurality of pins 5 about which the cables are looped, and a cable having one end attached to each pin and the other end attached to the fixed way

whereby said cable is adapted to withdraw the pin from between the cable loops during the launching operation at a point when the 10 poppets clear the end of the launching ways.

In testimony whereof I affix my signature.

JOHN JOSEPH SCOLLAN.
